UNITED STATES PATENT OFFICE.

HERBERT BENJAMIN SMITH, OF BROOKLYN, NEW YORK.

GAME APPLIANCE.

Application filed June 10, 1922. Serial No. 567,248.

To all whom it may concern:

Be it known that I, HERBERT B. SMITH, a citizen of the United States, and resident of the city of New York, borough of Brooklyn, county of Kings, and State of New York, have invented a new and Improved Game Appliance, of which the following is a full, clear, and exact description.

My invention relates to a game appliance and aims to provide a member of this type more particularly in the nature of a bat or striking member, which will present certain improvements over devices of this character heretofore placed upon the market.

It is an object of the present invention to provide a game appliance of the nature stated which may be associated with the hand of a player, and by means of which such games as hand ball, punch ball, etc., may be played in a more lively manner than has heretofore been possible, aside from the fact that the hand of the player will be prevented from being bruised or otherwise injured.

A further object of my invention is that of constructing a device of the character stated by means of which more velocity may be imparted to the ball than has been heretofore possible, by the usual method of projecting the ball solely by the hand.

Among further objects of my invention are that of providing a bat which will be capable of being constructed at a nominal figure and which will fit into the hand so that a wearer will not be handicapped by utilizing the same.

With these and further objects in mind my present invention embraces a game appliance in the nature of a bat comprising a body adapted to be grasped by the hands of the player, which body may be strapped to the hand if this is desired.

Reference is had to the attached sheets of drawings as illustrating one practical embodiment of my invention and in these views it will be seen that;

Figure 1 is a rear view of a player's hand having my improved appliance associated with it.

Figure 2 is a side elevation of the game appliance.

Figure 3 is an end view thereof.

In these views it will be noted that the reference numeral 11 indicates the body of the appliance which may be associated with

the hand 12 of a player by the provision of an angular strap 13 attached to the said body 11, this strap being retained upon the rear face of the body in the form of two minor end loops 14 and a major central loop 15 whereby the central portion of the hand may be inserted to a point between the major loop 15 and the rear of the body 11, while the little finger and thumb pass through both of the end loops thus affording an ideal means of attaching the appliance to the hand.

With a view of causing the body 11 to snugly bear against the palm of the player so that the body is virtually rigid with the hand I prefer to convex the rear face of the body 11, as has been indicated at 16, and thus it will be obvious that the player's hand will curve around this rear face and the convexity of the same will fall into the concavity of the palm.

Further it will be noted that I conveniently shape the outer or plain face of the appliance to also present a convexity 17 and by this expedient it will be understood that first a great amount of skill will be necessary in order to direct a projectile, such as a ball, which is struck by this face, and also a far greater velocity will be imparted to the ball when thus struck so that the game will be greatly enlivened, it being further understood in this connection that the body 11 may be formed of any suitable material which may further enhance the results in this connection.

From the foregoing, it will be seen that there is provided a wafer-like bat body 11 which is gibbous in any cross-section, that is, outwardly bulged or rotund on opposite sides of its plane of general flatness.

Thus the objects of this invention are accomplished it being of course understood that the strap 13 may have its loop portions rendered adjustable by the provision of slideable connecting means such as staples 18, which slidably embrace the strap and divide the loop portions one from the other so that these loop portions will adapt themselves to the various sizes and contours of the player's hand, it being further understood that incident to the angular disposition of the strap that the outer playing face of the body 11 is presented at a more efficient angle for the purposes of playing.

It will be obvious that numerous modifi-

cations of structure might readily be resorted to without in the least departing from the scope of my claims; which are;

1. A game appliance in the nature of a bat including a body gibbous in cross-section.
2. A game appliance in the nature of a bat including a body more flattened in one plane than in another and adapted to be nested in the palm of the hand immediately in rear of a striking surface on the forward face of the bat, which surface is convex.
3. A game appliance in the nature of a bat including a body presenting a convex

rear face and a convex playing face, said body having a width approximately twice its length.

4. A game appliance in the nature of a wafer-like bat body, and including, in combination with said body, means on the rear face of the body for mounting the bat in the player's hand and including a plurality of finger anchorages, said anchorages including adjustable loops forming a part of a common strap presenting a longer intermediate loop for a plurality of adjoining fingers of the hand.

HERBERT BENJAMIN SMITH.
